(No Model.)

L. WOERNER.
STEAM TRAP.

No. 451,547.

Patented May 5, 1891.

Fig. 1.

Fig. 2.

UNITED STATES PATENT OFFICE.

LEO WOERNER, OF ST. LOUIS, MISSOURI.

STEAM-TRAP.

SPECIFICATION forming part of Letters Patent No. 451,547, dated May 5, 1891.

Application filed January 15, 1891. Serial No. 377,791. (No model.)

To all whom it may concern:

Be it known that I, LEO WOERNER, a citizen of the United States, residing at St. Louis, in the State of Missouri, have invented a certain new and useful Improvement in Steam-Traps, of which the following is such a full, clear, and exact description as will enable any one skilled in the art to which it appertains to make and use the same, reference being had to the accompanying drawings, forming part of this specification.

My invention relates to that class of steam-traps which are controlled by the expansion and contraction of metal.

15 The present invention pertains more particularly to an expansion-joint for the casing of the trap and to a means for arresting the foreign matter in the steam and blowing it off.

The invention will be best understood by 20 referring to the accompanying drawings, in which—

Figure 1 is a view, partly in section, of a steam-trap made in accordance with my invention. Fig. 2 is a section thereof on the 25 line 2 2 of Fig. 1, looking in the direction of the arrow to said line; and Fig. 3 is a section on the line 3 3 of Fig. 1, looking in the direction of the arrow to said latter line.

5 is a pipe which is adapted to be placed 30 in communication with the eduction or exhaust pipe of any steam apparatus. This pipe takes into a T-joint 6, into which enters at one side a pipe 7, having a nose 8 projecting well into said T-joint, the said nose 8 being adapted to catch any dirt or grit that is 35 contained in the steam and cause it to pass into the pipe 7, from where it may be blown off from time to time by opening at will a valve 9, located in said pipe 7. From the T-joint 6 also leads a pipe 10 to an elbow 11, that opens into the steam-trap proper. The elbow 11 is joined to a coupling 12 by a short 40 piece of pipe 13. The said coupling 12 is formed in a casting having radial arms 14, 45 the purpose of which will be explained hereinafter. This coupling joins the pipe 13 to the pipe 15, which is in turn connected to a coupling 16, carried by a casting having radial arms 17. The coupling 16 is in turn 50 joined to a tube 18, the head 19 of which is secured in a casting 20, having radial arms

21. The respective radial arms 14, 17, and 21 of the various castings are joined together by rods 22 22. Within the tube 18 is a perforated pipe 23, one end of which is secured to 55 the head 19 of the tube 18, and the other end of which carries a valve 24, which is adapted to come against a seat formed in the coupling 16. From the tube 18 leads a pipe 25 for discharging the water of condensation from the 60 trap. Normally the valve 24 is open, and steam entering the tube 18 through said valve causes the perforated pipe 23 to expand and close said valve. As soon as the steam has 65 condensed the perforated pipe 23 cools and opens the valve 24, allowing more steam to enter the tube 18. The water of condensation escapes from the trap through the pipe 25.

I am aware that this principle of operation is old and well known and do not wish to be 70 understood as claiming the same, my invention relating to providing the casing-tube 18 with an expansion-joint to compensate for its expansion and contraction, the absence of which in previous constructions often interferes with the successful operation of steam-traps.

To carry out the purposes of my invention I divide the tube 18 transversely of its length, and to the opposite separated edges thereof I 80 secure the inner peripheries of annular plates 26, the outer peripheries of which are secured to a ring 27 by bolts 28. This construction permits the two parts of the tube 18 to lengthen or shorten by reason of expansion and contraction, the total length from one extreme end to the other always remaining the same, and the difference in length of the two parts being compensated for by the expansion-joint described. The operation of the valve 90 24 and the action of the trap are not, therefore, interfered with; but the opening and closing of the valve depends solely upon the expansion and contraction of its own perforated stem. All the parts of the said trap are 95 preferably made of brass.

Having fully described my improvements, what I desire to claim and secure by Letters Patent of the United States as my invention is—

1. A steam-trap consisting of a perforated metal pipe, a valve carried thereby at one end

controlling the admission of steam to said trap, a divided tube surrounding said perforated pipe, an expansion-joint intermediate 5 the adjacent ends of the divided tube, and a water-discharge pipe leading from the surrounding divided tube.

2. A steam-trap consisting of a perforated metal pipe, a valve carried thereby at one end controlling the admission of steam to said trap, a divided surrounding tube therefor, 10 annular plates fastened to the adjacent separated edges of said divided tube, the outer peripheries of which are suitably joined together, and a water-discharge pipe leading 15 from said surrounding tube.

3. The combination, to form a steam-trap, of a pipe 15, a divided tube 18, the couplings

12 and 16, the head 19, the radial arms 14, 17, and 21, the rods 22, joining the radial arms together and bracing the parts of the trap together, the perforated pipe 23 in said divided tube 18, a valve carried thereby, a water-discharge pipe 25, leading from said divided tube 18, and an expansion-joint connecting the two parts of the divided pipe together, substantially as and for the purpose described. 20 25

In testimony whereof I have hereunto set my hand and affixed my seal, this 12th day of January, 1891, in the presence of the two subscribing witnesses.

LEO WOERNER. [L. S.]
